UNITED STATES PATENT OFFICE.

HENRY C. RAHMOELLER, OF ST. CHARLES, MISSOURI.

GAUGE FOR DUPLICATING KEYS.

Application filed April 12, 1922. Serial No. 551,979.

To all whom it may concern:

Be it known that I, HENRY C. RAHMOELLER, a citizen of the United States, residing at St. Charles, in the county of St. Charles and State of Missouri, have invented certain new and useful Improvements in Gauges for Duplicating Keys, of which the following is a specification.

My invention relates to a device for duplicating keys, which makes the cutting of the key not only a very simple operation, but also a very accurate one, taking less time than ordinary key-cutting, as no special fitting is required and no time-wasting measuring or caliper is necessary.

One advantage of this invention resides in the fact, that there need be no wasting of material or cancellation of blanks, as the device prevents the operator from filing or sawing deeper than what is required.

The object of the invention is to provide a device in which an original or pattern key is clamped and in which a blank, from which the duplicate key is to be made, is also secured in the same manner. This device includes a gauge proper adjusted therein in relation to the pattern key and its curvature and indentations. By means of a suitable file or saw the required cuts are then produced in the blank and no matter how long the operator continues the filing or sawing, he cannot spoil the work, because the gauge does not permit a deeper cut in the blank than necessary.

In the accompanying drawings:

Figure 1 shows an assembled view of the device with the pattern key and blank in position;

Fig. 2 is a bottom plan view of Fig. 1;

Fig. 3 is a perspective view showing details of the device;

Fig. 4 is a similar view to Fig. 1 showing the application of the device for cutting flat keys;

Fig. 5 is a perspective detail view of the gauge;

Fig. 6 shows different forms of guide rollers for the gauge, and

Fig. 7 is a perspective view of a modified form of gauge edge.

Referring first to Figs. 1, 2 and 3 of the drawings, the device consists of a housing 10 which is constructed of a base or block 11, at one end of which a bridge 12 is attached by means of rivets or screws 13. This bridge has two end lugs 14, so that the in-

termidate portion of the bridge is raised a certain distance above the base 11 forming a rectangular aperture 15 between the bridge and the block. In this bridge are provided two threaded openings 16 and 17, each adapted to receive a thumb screw 18 for clamping the pattern key 19 and the blank 20, respectively, in position on the block. The inner face 21 of the block 11 is plain with exception of two raised abutments 22 and 23 having straight longitudinal abutment faces 24 and 25, respectively, running parallel to each other. At right angles to these abutment faces the abutments 22 and 23 have other abutment faces 26 and 27 which are positioned in alinement with each other. Between the abutments 22 and 23, and adjacent the latter, is provided a longitudinal guide groove 28 running from end to end of the block and the function of which will be described later. As best seen in Figs. 1 and 2, the pattern key 19 is inserted between the bridge 12 and the block 11 so as to rest on the plain surface 21 with its straight edge along the longitudinal abutment face 24 and its shoulder resting against the transverse abutment face 26 and thus clamped down by means of the thumb screw 18. Similarly the blank 20 is laid on the plain surface 21 of the block 11 with its straight back along the longitudinal abutment face 25 and its shoulder pushed up against the transverse abutment face 27 and then similarly clamped down by means of its thumb screw, as indicated to the left of Fig. 1.

It will be noted by reference to Figs. 1 and 3 that the abutment face 25 lies only slightly below the top face 29 of the block and runs parallel therewith, so that the edge of the blank, which is going to be shaped in accordance with the pattern key 19, extends above the face 29 a sufficient height, which must be greater than the distance from the front of the pattern key to its deepest indentation.

The gauge proper consists of a spike-like arm 30 with a pointed edge 31 adapted to engage with any part of the actuating edge of the pattern key 19. As best seen in Fig. 3, the arm has at its upper end a side projection 32, which is bent upwardly to form a yoke 33 and then back to form a bearing 34 for a guide roller 35. At the top of the arm 30 is another bearing 36 for a second roller 37. The rollers illustrated in Figs.

1 and 3 have a V-shaped groove 38 and they are so positioned that these grooves are in alinement and situated in the same plane as the edge 31 of the gauge and this plane A—A, 5 see Fig. 1, runs perpendicularly to the surface 21 of the block 11 when the gauge is assembled in position thereon. The distance measured from the sharp edge 31 of the gauge to the bottom of the groove 38 and the 10 upper side of the rollers 35 and 36 coincides exactly with the distance between the abutment surfaces 24 and 25.

Reference numeral 40 indicates a slide having a transverse aperture 41 adapted to 15 engage the gauge arm 30 and permitting a reciprocation thereon in the direction of the plane A—A in Fig. 1. This guide has a rib 42 of the same width as the guide groove 28 in the block 11, permitting longitudinal 20 sliding of the guide therein and a shank 43 is adapted to project through a slot 44 provided therefor in the bottom of the guide groove 28 of the block 11, in such a manner, that the shank 43 projects through the same 25 and may receive a washer 45 and a wing nut 46 for the purpose of clamping the guide in any suitable position longitudinally on the block 10.

It will now be readily understood, that by 30 setting the guide in a position with regard to the pattern key 19, so that the edge 31 of the gauge arm 30 engages with any desired part of the pattern key, as, for instance, in the bottom of a notch 47 of the key; the 35 distance from the shoulder of the blank to the grooves 38 in the rollers, will be exactly the same as the corresponding distance from the shoulder of the pattern key to the notch 47; and that the distance from the bottom of 40 groove 38 in the guide rollers 35 and 37 to the abutment face 25 will be exactly the same as the distance of the notch 47 above the back face of the pattern key or abutment face 24. By now applying a file to 45 the blank this notch 47 will be duplicated therein and it will be seen that the file can cut no deeper, than the rollers 35 and 37 will permit and by using a file of approximately the same shape as the notch 47, that is, as seen in Fig. 1, a triangular file 48, the exact 50 shape of the notch 47 will be reproduced in the blank. It will also be understood, that by shifting the guide 40 opposite the next notch in the pattern key, that notch will similarly be reproduced in the blank and that 55 in this manner the entire profile of the pattern key, whether notches or swells, may be copied from the blank.

When using the device the block 11 is 60 preferably placed in a vise, having the position shown in Fig. 1, with the rollers as indicated to the left of the figure or with the rollers on top of the device.

In Figs. 4 and 5 a differently shaped gauge arm 50 is used in the slide 40 but clamped

in the same manner, as described above, in the block 11, which, as before, is provided with longitudinal abutment faces 24 and 25, transverse abutment faces 26 and 27 and a guide groove 28. This gauge arm terminates with a flat knife-edge 51 and is intended for the use in cutting flat keys 52 having rectangular notches 53 instead of V-shaped or concave ones, as indicated in Fig. 1. As these notches may vary in width from about one-sixteenth to three-sixteenths of an inch, I prefer to use an adjustable jaw 54 at the upper end of the gauge arm 50 and this jaw is accordingly provided with a shoulder 55 adapted to seat on the flat faced seat 56 on the gauge 50 so as to be slidable in transverse direction of the gauge and clamped in position thereon by means of a set screw 57 engaging in a groove 58 in the jaw 54 and threaded, as at 59, in the seat 56. This gauge 50 is also provided with a yoke 60 having a bearing 61 for a roller 62, another roller 63 being inserted between the yoke 60 and the seat 56 and the two rollers being at the same height above the knife-edge 51 of the gauge.

The inner side 64 of the yoke 60 and the side 65 of the knife-edge 51 run in alinement with each other and the jaw 54 is adjustable with regard to this side 64 for determining the width of a slot to be cut in the blank so that, when the side 65 of the knife-edge is pressed against one side of a notch 53 in the pattern key and the guide 40 clamped in such position, the distance of the notch will be accurately located from the shoulder of the key to the same position on the blank.

In Fig. 6 has been illustrated different kinds of rollers, that may be used in my device, reference numeral 66 denoting a roller with V-shaped groove similar to rollers 35 and 37 indicated in Figs. 1 and 3. This groove may be deeper or shallower, as required by the work. Reference numeral 67 denotes a roller with a concave groove for notches of this character, when a cylindrical file is preferably used. The reference numeral 68 denotes a cylindrical roller to be used in connection with the adjustable jaw 54 in the gauge 50.

To produce round bottomed notches in connection with roller 67, the gauge arm 30 has to have a rounded edge. For this purpose the edge portion 31 is preferably detachable from the arm as seen in Fig. 3 and a round edge 69, see Fig. 7, substituted. These edges are made interchangeable and provided with a seat 70 engaging with the end of the gauge arm 30 and a set screw 71 having its head countersunk in the side of each edge secures the edge rigidly in the arm.

When the notches are very narrow, it is preferable to use a saw blade 76 for cut-

ting the notches or grooves, as indicated in Fig. 4, and various kinds of saw blades or files should be used for differently shaped notches.

5 It will be evident that the invention is applicable not only for use in duplicating keys, but may also be useful in copying profiles of various kinds, which are difficult to measure and duplicate in an ordinary manner. It will also be evident that the copy will be perfectly accurate as the files or saws cannot enter deeper into the blank, than what the rollers will permit and the rollers being made of glass-hard material will not dull or destroy the tools. By the use of my device it will be possible for an unexperienced operator to produce a duplicate key from the original pattern very accurately and without being able to spoil 20 the work.

Having thus described the invention, what is claimed as new is:

1. A key duplicating device, comprising a housing, longitudinal abutments in said housing adapted to receive a key pattern and a blank in parallel relation to each other, clamps for rigidly holding the pattern and the blank in such relation, a guide being formed in said housing running parallel to the longitudinal abutments, a gauge member having a pattern engaging edge, a bearing for said gauge member permitting reciprocation thereof relatively to said lateral abutments, and means for adjustably securing said bearing in said guide, a pair of rollers on said gauge member adjacent the abutments for the blank, adapted to limit the cutting action of a tool, said rollers having grooves situated in a plane running through said edge and a straight line connecting the bottoms of said grooves running parallel to said edge.

2. A key duplicating device, comprising a housing, longitudinal and lateral abutments

in said housing adapted to receive a key pattern and a blank in parallel relation to each other, clamps for rigidly holding the pattern and the blank in such relation, a guide being formed in said housing running parallel to the longitudinal abutments, a gauge member having a pattern engaging edge, a bearing for said gauge member, permitting reciprocation thereof relatively to said lateral abutments, and means for adjustably securing said bearing in said guide, 55 rollers on said gauge member adjacent the abutments for the blank, adapted to limit the cutting action of a tool, said rollers having grooves situated in a plane running through said edge and parallel to said lateral abutments, said lateral abutments being in alinement with each other.

3. A key duplicating device comprising a housing, longitudinal and lateral abutments in said housing adapted to receive a key pattern and a blank in parallel relation to each other, clamps for rigidly holding the pattern and the blank in such relation, a guide being formed in said housing running parallel to the longitudinal abutments, a 65 gauge member having a pattern engaging edge, a bearing for said gauge member permitting reciprocation thereof relatively to said lateral abutments, and means for adjustably securing said bearing in said guide, 70 rollers on said gauge member adjacent the abutments for the blank, adapted to limit the cutting action of a tool, said rollers having grooves situated in a plane running through said edge and parallel to said lateral abutments, said lateral abutments being in alinement with each other, and said longitudinal abutments being spaced apart a distance identical with the distance from 80 said edge to the operating side of said 85 grooves.

In testimony whereof I affix my signature.
HENRY C. RAHMOELLER.
